ROBERT S. PEELLE, OF HOLLIS, NEW YORK, ASSIGNOR TO THE PEELLE COMPANY, OF BROOKLYN, NEW YORK, A CORPORATION OF NEW YORK

OPERATOR FOR BIPART SLIDEUP DOORS

Application filed April 10, 1931. Serial No. 529,264.

My invention relates to operators for bi-part slideup doors, and more particularly to an electric motor driven operator including the means of applying the power of the motor to the two sections of the door in a manner to secure the desired differential speed of movement of the door sections during both their opening and their closing movements so as to have both parts or sections of the door arrive substantially simultaneously at the fully open or fully closed position.

The construction and mode of operation of a bi-part slideup door must be understood to permit an appreciation of the construction and mode of operation of the operator of the invention.

A bi-part slideup door, as known to the elevator door art, consists of two sections mounted upon tracks arranged in parallel vertical planes. The upper section closes the upper part of the door opening and the lower section closes the lower part of this opening. The guides for such doors are usually positioned upon the floor side of a door opening. Hence both sections are positioned at the door opening upon the floor side of the wall.

When the door is closed, the lower section rests upon the floor of the building. When the door is open, the lower edges of both sections are in substantially the same plane at or adjacent the lintel of the opening. These doors are ordinarily used to close openings of elevator shafts where space within the shaft is not available for the mounting of doors, or where the building construction is such as to preclude the use of other types of doors.

There are two general constructions of bi-part slideup doors. In both, counterweights are provided on each side of the door. In one the constructive counterweights are supported by sprocket chains which pass over sprocket wheels upon shafts above, and at opposite sides of, the door. Carried by each shaft having a sprocket wheel are two other sprocket wheels, one of which is twice the diameter of the other. Passing about the smaller sprocket wheel upon each shaft is a sprocket chain connected with the upper door

section. Passing about the larger sprocket wheel is a sprocket chain which is connected with the lower door section.

In the other construction, at each side of the door are two sheaves of the same diameter. A chain is provided at each side of the door structure, one dead end of each chain being connected to a fitting adjacent the sheaves, and the other dead end being connected to the lower door section. This chain has a slip or equalizing connection with a counterweight, and from the counterweight passes about a sheave upon the upper door section. In this manner, force for opening or closing the door, aided by the counterweights, will cause the upper door section to move at one-half the speed of the lower door section by reason of the second class pulley system in the connection between the counterweight and the upper door section.

So far as I am aware, no power operator has ever been used with either of the constructions above referred to.

The main object of the invention is to provide an electric motor driven operator where in power is applied through a single mechanism to both sides of both the lower, and the upper section of the door, the power of the electric motor being supplemented by a single counterweight to which the flexible connections or chains for applying the power of the motor to the door are fixedly connected.

In the operator of the invention, the arrangement of the flexible connections or chains, in relation to the operator and the counterweight and to the two door sections, is not only such as to ensure the distribution of the stresses developed by the motor and the power member actuated thereby upon both sides of the door, but that differential speed of the two door sections essential to an unvarying load upon the motor and a desired speed of operation of the door.

In carrying out the invention, I employ what may be termed a three-chain system, two of the chains of which are operative only as to the lower section, and the third chain of which is operative only as to the upper section.

The construction of the operator is also

such that the entire running gear is so positioned as to avoid possibility of tampering therewith, the various parts being so positioned and so formed that possibility of such 5 disarrangement thereof as will interfere with the operation of the door is reduced to a minimum.

Furthermore, the manner of applying the power to the upper door section is such as 10 to permit the various mechanisms to be applied to the top edge of the door, thus avoiding the weakening of the door structure proper at the point of application of power thereto, as well as the difficulties and expense 15 of embodying these mechanisms in the door proper.

In an operator of the invention, the various parts are so constructed as to avoid the necessity for the making of any changes in 20 the guide structure, it being possible to apply the operator to doors which are already installed by merely changing the supporting chains and slightly increasing the weight of one of the counterweights, the other counter- 25 weights being entirely dispensed with. In so applying an operator of the invention, it would also be necessary to remove the sprocket wheels or sheaves commonly used in such doors, and replace them with the sheave and 30 dead end stop fittings, to be hereinafter referred to.

A still further object is to provide an operator of the type herein referred to, the construction and arrangement of parts of which 35 is such as to permit the manual operation of the door in the event of failure of the motor power, thus avoiding all those delays and inconveniences which would result from inability to open or close the door in such an emergency.

The invention consists primarily in an operator for bi-part slideup doors embodying therein a power sheave adjacent one side of the door, a guide sheave adjacent the other 45 side of the door, a counterweight, a chain connected with said counterweight and passing about said power sheave to one side of the lower section of a door, a second chain connected with said counterweight and passing 50 about said power sheave and said guide sheave to the other side of the lower section of a door, sheaves secured adjacent the top and at opposite sides of an upper door section, a 55 dead end fitting, a third chain passing from said dead end fitting about said sheaves carried by the upper door section and said power sheave and connected with said counterweight, an electric motor, gearing connecting 60 said motor with said power sheave, an electric source supplying power to said motor, and a pole changing switch mechanism controlling the power from said source; and in 65 such other novel features of construction and combination of parts as are hereinafter set

forth and described, and more particularly pointed out in the claims hereto appended.

Referring to the drawings,

Fig. 1 is a vertically and laterally condensed view in elevation of a bi-part slideup 70 door, and an operator applied thereto;

Fig. 2 is a section on the line 2—2 of Fig. 1;

Fig. 3 is a plan view of Fig. 1 showing the wall in section;

Fig. 4 is an enlarged view of the motor, the 75 power sheave and a portion of the chains adjacent the power sheave; and

Fig. 5 is a diagrammatic showing of the electrical conditions in the operator.

Like numerals refer to like parts throughout the several views.

In the embodiment of the invention shown in the drawings, the upper door section is shown at 10 and the lower door section at 11. The guide rail structure 12 is of the usual, or may be of any desired, construction, so that a detailed description thereof is unnecessary, beyond that such structures include parallel guides along which the sections 10 and 11 respectively have movement 90 in the same direction. The movement of said sections is simultaneous, but the lower section is required to travel at twice the speed of the upper section, so that both sections will come to rest with their lower edges in substantially the same plane adjacent the lintel of the door opening when the door is open, and during the closing movement, the upper section will come to rest with its lower edge at substantially the middle of the height 100 of the door opening at substantially the same time that the lower section comes to rest at the sill of the door opening.

In the drawings, the sill of the door opening is indicated at 13, the lintel of the door opening at 14, and the side jambs of the door opening at 15. The guide rail structures 12 are connected to the wall 16 adjacent each jamb 15.

Carried by the guide rail structure adjacent one jamb is a power sheave 17, and carried by the guide rail structure adjacent the other jamb is a guide sheave 18. The power sheave 17 is a wide sheave.

Below the power sheave 17 is a casing 19 for a counterweight 20. The movements of this counterweight equal the movements of the lower door section.

Connected with the counterweight 20 is a chain or other flexible connection 21 which passes about the power sheave 17 and extends downwardly from this sheave to a fitting carried by the lower door section 11 adjacent the top thereof, to which fitting the chain is permanently connected. A second chain 22 is also connected with the counterweight 20 and passes therefrom about the power sheave 17 and the guide sheave 18, the end thereof being permanently connected to a fitting adjacent the top of the lower door section 11 130

upon the opposite side of said section to that at which the chain 21 is connected.

Mounted upon one guide rail structure 12 adjacent the guide sheave 18 is a dead end fitting 23. Carried by the top of the upper door section 10 adjacent the opposite edges thereof are guide sheaves 24 and 25. Secured to the dead end fitting 23 is a third chain 26 which passes downwardly from this fitting about the guide sheaves 24 and 25 and upwardly and about the power sheave 17 to the counterweight 20 to which this chain is also connected.

It will be noted that there are three power transmitting chains in the operator of the invention, the chains 21 and 22 being connected to the counterweight 20 and to the lower door section, while the chain 26 is connected to the counterweight 20 and applies power through a running connection with the upper door section 10 by a sheave arrangement similar to a pulley construction of the second class.

The sheaves 24 and 25 ensure the simultaneous application of lifting power, during the opening movement of the door, to opposite sides of the upper door section, and a travel of this section at one-half the speed of the lower door section, by reason of the dead end of the chain 26 being connected to the fitting 23. It will be noted that the chain 26 between the sheaves 24 and 25 is positioned closely adjacent the top of the upper door section, the width of this section being such that this chain is protected by the top of the section 10, being in fact almost concealed from view even when the door is in the closed position.

The power sheave 17 is mounted in a housing 27 mounted upon one guide rail structure. Also mounted within this housing is a small polyphase inductive motor 28, the armature of which has a small pinion 29 enmeshed with a spur gear 30 forming one of the shrouds of the power sheave 17. This construction not only protects the working parts of the power unit from accumulated dust and dirt, but avoids possibility of a disarrangement of parts in the unit which might interfere with a proper continued operation of the unit.

Only one power unit is used in the operator since the type of motor used is capable of operating at low speeds with a high torque. It is of a special construction, however, which is adapted only for a short run of the motor, which at the most never extends over a period of more than a few seconds.

The guide rail structure adjacent the housing 27 is cut away to permit the projection of the power sheave through this structure so as to allow a clear field for the run of the chains 21, 22 and 26 between the sheave and the door sections. The housing 27 also acts

as an outlet box, being provided with suitable outlet openings to permit the running of the electric lines from the source to the motor.

The sheaves 24 and 25 are each mounted between a plate 31 securely bolted through the panel of the upper door section and the angle metal frame of this section, and an angle plate 32 securely bolted to the top bar of the frame of the upper door section.

Bi-part slideup doors are generally used for closing the lowermost opening of an elevator shaft, and the usual practice is to control the application of power for opening and closing such doors by a switch mechanism located within the car. The location of this switch mechanism, however, is immaterial to the invention which merely requires that a conveniently accessible switch be used by which power may be applied to the motor in a manner to cause it to be rotated in the desired direction to effect either the opening or the closing of the door. In other words, the motor 28 is a reversible motor, and an opening and a closing switch mechanism is used in order to impress a current of the desired polarity upon the motor.

In the accompanying drawings, I have illustrated one arrangement of wiring which may be used with the operator, but I do not wish it understood that this particular method is essential to the invention.

In Fig. 5 of the drawings the circuit to the motor 28 is controlled by a switch 33 actuated by a cam 34 on the car. This is used merely to prevent the opening of the door unless the elevator car carrying the cam 34 is at the opening. If the door be used otherwise than in connection with an elevator shaft, this switch is not required.

The lines of the three-phase source are indicated at 35, 36 and 37. These lines communicate by the branch lines 38, 39 and 40 with the fixed contacts 41, 42 and 43 of a magnetic switch having movable contacts 44, 45 and 46 actuated by means of a magnet 47 and acted upon by a spring 48 having a normal tendency to open the switch.

One terminal of the winding of the magnet 47 is connected by a lead 49 with the branch line 38 and the line 35 from the source through the lead 50. The other terminal of said winding is connected by the lead 51 with one terminal of a limit switch 52, the other terminal of which is connected by the line 53 with one terminal of an opening switch 54 which may be carried by an elevator car, or otherwise located, as desired. The other terminal of this opening switch is connected by the lead 55 with the branch line 40 and the line 37 from the source.

The movable contacts 44, 45 and 46 are connected to shaft service lines 56, 57 and 58, which may serve a number of doors in the shaft as well as that shown in the draw-

ings. The shaft line 58 is in direct electrical connection with one terminal of the motor 28 by the branch line 59. The shaft switch 33 has two sets of contacts, one set 60 having one terminal thereof connected with the line 56 by the lead 61, and the other terminal thereof connected by the line 62 with another terminal of the motor. The other set of contacts 63 of said switch 33 has one terminal 10 thereof connected with the line 57 by the lead 64, and the other terminal thereof connected with the third terminal of the motor by the line 65.

The lines 35, 36 and 37 are also connected 15 with fixed contacts 66, 67 and 68 of a closing switch having movable contacts 69, 70 and 71 electrically connected by the leads 72, 73 and 74 with the lines 56, 57 and 58 of the service line in the shaft. The contacts 69, 20 70 and 71 are actuated by a magnet 75, one terminal of the winding of which is connected by the lead 76 with one terminal of a closing switch 77, the other terminal of which winding is connected with the line 50. 25 The movable contacts 69, 70 and 71 are acted upon by a spring 78 having a normal tendency to open said closing switch.

In the diagram shown, the switches 54 and 77 are constant pressure switches requiring 30 the person using the switches to maintain the pressure upon the switch until the desired movement of the door has been completed. The limit switch 52 is used so as to cause the automatic interruption of the circuit to the 35 motor when the opening movement is completed, thus preventing a continued application of power to the motor after the door has been fully opened. Ordinarily, the moving inertia of the door sections and of the counterweight will permit the interruption of the 40 circuit prior to the full door movement. This condition may be relied upon when closing the door, and in fact, if desired, the final closing movement may be by hand. In opening the door, however, it is preferable to rely upon the limit switch.

The upper door section 10 is provided with a cam 79 adapted to engage the movable member of the limit switch 52 when the door has 55 reached its full opening movement.

The operation of a bi-part slideup elevator door equipped with an operator of the invention is substantially as follows:

Referring in Fig. 5 of the drawings, the 55 electrical conditions are those existant when the door is in the fully closed position. Assuming that the door is used closing an opening in an elevator shaft, the relation of parts would indicate that the elevator car is descending toward the opening closed by the door.

As the car reaches the opening, with its platform in substantially the plane of the sill 14, the shoe 34 acts to close the switch mechanism 33 and thus connect the service lines 56,

57 and 58 with the terminals of the motor 28 through the branch lines 59, 62 and 65. When the switch has thus been closed, power may be applied to the door for either opening or closing same, since the electrical conditions 70 established by the shoe 34 continue so long as an elevator car remains at the floor adjacent which is the switch 33.

The car attendant, when it is desired to open the door, merely depresses, and continues to depress, the control button of the switch 54 to close this switch. When the switch is closed, the following circuit is set up:

From line 37, through lead lines 40 and 55, to the switch 54, and from said switch 80 through the lead line 53, the limit switch 52 and lead line 51 to the winding of the magnet 47 and from said magnet through the lead lines 49 and 50 to the branch line 38 and the terminal 35. As the magnet 47 is energized, 85 the movable contacts 44, 45 and 46 are engaged with the fixed contacts 41, 42 and 43, thus permitting flow of the current from the lines 35, 36 and 37 of the source to the service lines 56, 57 and 58, and thence to the 90 terminals of the motor 28.

The motor will continue to operate until the shoe 79, by engagement with the limit switch 52, interrupts the circuit including the magnet 47, the de-energization of which 95 will permit the spring 48 to actuate the movable contacts to open the opening switch and thus interrupt the flow of current to the respective service lines 56, 57 and 58.

This will occur whether or not the pressure 100 upon the push button of the switch 54 is continued beyond the time required for the full opening movement of the door.

When it is desired to close the door, the switch 77 is actuated, thus closing the circuit 105 from the line 37 from the source through the lead line 51 to one terminal of the closing switch, from the other terminal of this switch through the line 76 to the winding of the magnet 75, and from the other terminal of this winding through the lead 55 to the branch line 38 from the line 35 of the source. As the magnet 75 is energized, the movable contacts 69, 70 and 71 are actuated to close the closing circuit, thus impressing upon the service lines 110 56, 57 and 58 current from the lines 36, 35 and 37 through the leads 73, 72 and 74.

It will be noted that this reverses the polarity of two of the lines running to the motor 115 28 and will thus cause the rotation of the motor in the reverse direction. The door will continue to move so long as the switch 77 is held closed, but as heretofore stated, in closing the door sections they will gather sufficient momentum to permit the opening of the switch 77 prior to the complete closing movement. Since no damage can be done when the door is fully closed, no limit switch need be used.

When power is applied to the motor for 130

opening the door, in the manner above described, the power sheave 17 is turned clockwise, as shown in Fig. 1, thus simultaneously taking up the chains 21, 22 and 26 which pass side by side about the sheave 17 which has a smooth periphery. At the same time, the length of the chains taken up will be paid out toward the counterweight 20. The load of the counterweight upon one side of the sheave 17, and the load of the door sections upon the other side thereof permit the elevation of both sections of the door by the application of very little power to the sheave. In fact a motor having only one-sixth H. P. is adequate to actuate doors weighing between one thousand and two thousand pounds, there being little or no tendency toward slippage between the chains and the power sheave.

20 As the doors reach the limit of their opening position, the shoe 79, by contact with the movable member of the limit switch 52, interrupts the circuit to the motor, immediately stopping the application of power to the doors.

By the arrangement of the guide sheaves 24 and 25 the chain 26 and the connection of this chain with the dead end fitting 23, the run of the chain 26 in relation to the power sheave is the same as that of the chains 21 and 22, but the movement of the section 10 is only at one-half the speed of that of the lower section 11. Since the two door sections 10 and 11 reach the limit of their opening movement substantially simultaneously, it is immaterial upon which section the cam 79 is mounted since it will be operative at substantially the same instant, irrespective of which door section carries it.

40 During the closing movement of the door, the action of the power sheave is the reverse of that heretofore described. By its counter-clockwise movement the sheave takes up the chains 21, 22 and 26 between it and the counterweight 20, and pays out this chain upon the door side of the guide structure, the counterweight being raised as a result of this action. The chains 21, 22 and 26 will have the same length paid out toward the door section, but owing to the pulley of the second class effect secured, the downward movement of the upper door section will be at only one-half the speed of the downward movement of the lower section.

55 It will be noted that the limit switch is arranged in the circuit including the opening switch only, so that when a door is fully open the electrical conditions are always such as to permit the application of closing power to the motor by means of the switch 77.

During both the opening and the closing of the door there is a run of the chain between the guide sheaves 24 and 25, but this reach of chain is very close to the top bar of the

upper door section, being almost in rubbing contact therewith.

The weight of the upper door section will always prevent a creation of such slack in the chain 26 as would permit its overrunning 70 the sheaves 24 and 25. The upper door section is suspended from the single chain 26.

The operation of my invention ensures a smooth, quiet movement of both door sections by a very simple arrangement of parts. 75 A motor developing very low power may be used, the total dimensions of the housing 27 and the parts carried thereby not exceeding fifteen inches in height or width, and being approximately eight inches in depth. It may 80 be conveniently attached to the guide structure in the shop, thus minimizing the labor of installation.

By using chains 21, 22 and 26 they may 85 be fairly accurately adjusted, and when once adjusted will develop so little stretch as to preclude the possibility of requirements for servicing arising from a loss of adjustment due to the chains.

The arrangement of chains and sheaves heretofore described, permits the manual operation of the door at any time, since the power sheave 17 is geared directly to the armature of the motor 28, which armature is free to turn with the sheave when no power is applied to the motor. Hence, in the event of failure of the power, the door may be opened or closed by hand as freely as though no operating motor were connected therewith. This is a highly desirable characteristic.

It is not my intention to limit the invention to any particular wiring arrangement since this may be varied at will to meet varying electrical conditions.

It is also apparent that the details of construction shown in the accompanying drawings may be varied without departing from the spirit and scope of the invention.

Having described the invention, what I claim as new and desire to have protected by Letters Patent, is:—

1. An operator for bi-part slideup doors embodying therein a power sheave adjacent one side of the door, a guide sheave adjacent the other side of the door, a counterweight, a chain connected with said counterweight and passing about said power sheave to one side of the lower section of a door, a second chain connected with said counterweight and passing about said power sheave and said guide sheave to the other side of the lower section of a door, sheaves secured adjacent the top and at opposite sides of an upper door section, a dead end fitting, a third chain passing from said dead end fitting about said sheaves carried by the upper door section and said power sheave and connected with said counterweight, an electric motor, gearing connecting said motor with said

power sheave, an electric source supplying power to said motor, and a pole changing switch mechanism controlling the power from said source.

2. An operator for bi-part slideup doors embodying therein a guide rail structure upon each side of a door opening, a housing mounted upon one of said guide rail structures, a power sheave mounted in said housing, a guide sheave carried by the other guide rail structure, a counterweight, a chain connected with said counterweight and passing about said power sheave to one side of the lower section of the door, a second chain connected with said counterweight and passing about said power sheave and said guide sheave to the other side of the lower section of the door, sheaves secured adjacent the top and at the opposite sides of the upper door section, a dead end fitting carried by the guide rail structures carrying said guide sheave, a third chain passing from said dead end fitting about said sheaves carried by the upper door section and said power sheave, and connected with said counterweight, an electric motor within said housing, gearing connecting said motor with said power sheave, an electric source supplying power to said motor, and a pole changing switch mechanism controlling the power from said source.

3. An operator for bi-part slideup doors embodying therein a power sheave adjacent one side of the door, a guide sheave adjacent the other side of the door, a counterweight, a chain connected with said counterweight and passing about said power sheave to one side of the lower section of a door, a second chain connected with said counterweight and passing about said power sheave and said guide sheave to the other side of the lower section of a door, sheaves secured adjacent the top and at opposite sides of an upper door section, a dead end fitting, a third chain passing from said dead end fitting about said sheaves carried by the upper door section and said power sheave and connected with said counterweight, an electric motor, gearing connecting said motor with said power sheave, an electric source supplying power to said motor, a pole changing switch mechanism controlling the power from said source, a normally closed limit switch having a movable contact arranged in the circuit to said pole changing switch mechanism, and a shoe carried by one of said door sections co-operating with said movable contact of said limit switch so positioned as to interrupt the circuit to said pole changing switch mechanism during the opening movement of said door.

4. An operator for bi-part slideup doors embodying therein a guide rail structure upon each side of a door opening, a housing mounted upon one of said guide rail struc-

tures, a power sheave mounted in said housing, a guide sheave carried by the other guide rail structure, a counterweight, a chain connected with said counterweight and passing about said power sheave to one side of the lower section of the door, a second chain connected with said counterweight and passing about said power sheave and said guide sheave to the other side of the lower section of the door, sheaves secured adjacent the top and at the opposite sides of the upper door section, a dead end fitting carried by the guide rail structures carrying said guide sheave, a third chain passing from said dead end fitting about said sheaves carried by the upper door section and said power sheave, and connected with said counterweight, an electric motor within said housing, gearing connecting said motor with said power sheave, an electric source supplying power to said motor, a pole changing switch mechanism controlling the power from said source, a normally closed limit switch having a movable contact arranged in the circuit to said pole changing switch mechanism, and a shoe carried by one of said door sections co-operating with said movable contact of said limit switch so positioned as to interrupt the circuit to said pole changing switch mechanism during the opening movement of said door.

5. An operator for bi-part slideup doors embodying therein a power sheave adjacent one side of the door, a guide sheave adjacent the other side of the door, a counterweight, a chain connected with said counterweight and passing about said power sheave to one side of the lower section of a door, a second chain connected with said counterweight and passing about said power sheave and said guide sheave to the other side of the lower section of a door, sheaves secured adjacent the top and at opposite sides of an upper door section, a dead end fitting, a third chain passing from said dead end fitting about said sheaves carried by the upper door section and said power sheave and connected with said counterweight, an electric motor, gearing connecting said motor with said power sheave, an electric source supplying power to said motor, a pole changing switch mechanism controlling the power from said source, including a normally open magnetic switch in the circuit from said electric source, a circuit from said source including the magnet of said switch, a manually operative switch in said last named circuit, a normally closed limit switch having a movable contact arranged in the circuit to said pole changing switch mechanism, and a shoe carried by one of said door sections co-operating with said movable contact of said limit switch so positioned as to interrupt the circuit to said pole changing switch

mechanism during the opening movement of said door.

6. An operator for bi-part slideup doors embodying therein a guide rail structure upon each side of a door opening, a housing mounted upon one of said guide rail structures, a power sheave mounted in said housing, a guide sheave carried by the other guide rail structure, a counterweight, a chain connected with said counterweight and passing about said power sheave to one side of the lower section of the door, a second chain connected with said counterweight and passing about said power sheave and said guide sheave to the other side of the lower section of the door, sheaves secured adjacent the top and at the opposite sides of the upper door section, a dead end fitting carried by the guide rail structures carrying said guide sheave, a third chain passing from said dead end fitting about said sheaves carried by the upper door section and said power sheave, and connected with said counterweight, an electric motor within said housing, gearing connecting said motor with said power sheave, an electric source supplying power to said motor, a pole changing switch mechanism controlling the power from said source, including a normally open magnetic switch in the circuit from said electric source, a circuit from said source including the magnet of said switch, a manually operative switch in said last named circuit, a normally closed limit switch having a movable contact arranged in the circuit to said pole changing switch mechanism, and a shoe carried by one of said door sections co-operating with said movable contact of said limit switch so positioned as to interrupt the circuit to said pole changing switch mechanism during the opening movement of said door.

7. An operator for bi-part slideup doors embodying therein a power sheave adjacent one side of the door, a guide sheave adjacent the other side of the door, a counterweight, a chain connected with said counterweight and passing about said power sheave to one side of the lower section of a door, a second chain connected with said counterweight and passing about said power sheave and said guide sheave to the other side of the lower section of a door, sheaves secured adjacent the top and at opposite sides of an upper door section, a dead end fitting, a third chain passing from said dead end fitting about said sheaves carried by the upper door section and said power sheave and connected with said counterweight, an electric motor, gearing connecting said motor with said power sheave, an electric source, service lines extending from said source to adjacent said motor, branch lines from said service lines to said motor, a normally open switch mechanism arranged in said branch lines and

adapted to be operated by a shoe upon an elevator car, and a pole changing switch mechanism controlling the power from said source.

8. An operator for bi-part slideup doors embodying therein a guide rail structure upon each side of a door opening, a housing mounted upon one of said guide rail structures, a power sheave mounted in said housing, a guide sheave carried by the other guide rail structure, a counterweight, a chain connected with said counterweight and passing about said power sheave to one side of the lower section of the door, a second chain connected with said counterweight and passing about said power sheave and said guide sheave to the other side of the lower section of the door, sheaves secured adjacent the top and at the opposite sides of the upper door section, a dead end fitting carried by the guide rail structures carrying said guide sheave, a third chain passing from said dead end fitting about said sheaves carried by the upper door section and said power sheave, and connected with said counterweight, an electric motor within said housing, gearing connecting said motor with said power sheave, an electric source, service lines extending from said source to adjacent said motor, branch lines from said service lines to said motor, a normally open switch mechanism arranged in said branch lines and adapted to be operated by a shoe upon an elevator car, a pole changing switch mechanism controlling the power from said source, including a normally open magnetic switch in the circuit from said electric source, a circuit from said source including the magnet of said switch, a manually operative switch in said last named circuit, a normally closed limit switch having a movable contact arranged in the circuit to said pole changing switch mechanism, and a shoe carried by one of said door sections co-operating with said movable contact of said limit switch so positioned as to interrupt the circuit to said pole changing switch mechanism during the opening movement of said door.

In witness whereof I have hereunto affixed my signature this 7th day of April, 1931.

ROBERT S. PEELE.
